UNITED STATES PATENT OFFICE

161,823

COMBINED MEASURING SPOONS AND WALL PLAQUE

Sidney Darwin, Woodbridge, N. J.

Application February 3, 1950, Serial No. 7,695

Term of patent 7 years

(Cl. D44—29)

To all whom it may concern:

Be it known that I, Sidney Darwin, a citizen of the United States, residing at Woodbridge, in the county of Middlesex, and State of New Jersey, have invented a new, original, and ornamental Design for a Combined Measuring Spoons and Wall Plaque, of which the following is a specification, reference being had to the accompanying drawing, forming part thereof.

In the drawing:

Fig. 1 is a front perspective view of a combined measuring spoons and wall plaque, showing my new design;

Fig. 2 is a side elevational view of the same; and

Fig. 3 is an exploded perspective view.

I claim:

The ornamental design for a combined measuring spoons and wall plaque, as shown.

SIDNEY DARWIN.
